DESIGN FOR A SERVING TRAY

David H. McAlpin Pyle, Far Hills, N. J.

Application October 30, 1933. Serial No. 49,604

Term of patent 14 years

To all whom it may concern:

Be it known that I, DAVID H. MCALPIN PYLE, a citizen of the United States, residing at Far Hills, county of Somerset, and State of New Jersey, have invented a new, original, and ornamental Design for a Serving Tray, of which the following description in connection with the accompanying drawing is a specification.

Fig. 1 is a top plan view;
Fig. 2 is a side elevation; and
Fig. 3 is a rear elevation of a tray showing my design.

I claim:
The ornamental design for a serving tray, substantially as shown.

DAVID H. MCALPIN PYLE.
